UNITED STATES PATENT OFFICE.

CHARLES E. PARKER, OF DULUTH, MINNESOTA.

TRUNK-LOCK.

SPECIFICATION forming part of Letters Patent No. 588,237, dated August 17, 1897.

Application filed August 22, 1896. Serial No. 603,603. (No model.)

To all whom it may concern:

Be it known that I, CHARLES E. PARKER, a citizen of the United States, residing at Duluth, in the county of St. Louis and State of Minnesota, have invented certain new and useful Improvements in Locks for Trunks and other Receptacles; and I do hereby declare the following to be a full, clear, and exact description of the invention, such as will enable others skilled in the art to which it appertains to make and use the same.

This invention relates to improvements in that class of locks intended for use more especially in trunks and satchels.

15 The objects of my invention are to provide a trunk or satchel with a safe and convenient means for locking the same, to avoid the necessity of employing trunk-straps or auxiliary fastening devices of any kind, to locate the 20 entire locking means within the trunk, thus avoiding accidental breaking by careless handling, and, finally, to provide a safe, simply-constructed, and economically-manufactured lock that is not only adapted to secure the 25 trunk-lid or satchel at its center, as is usual, but also at its opposite ends.

Other objects and advantages of the invention will hereinafter appear, and the novel features thereof will be particularized in the 30 appended claims.

Referring to the drawings, Figure 1 is a front elevation of a trunk, the same being provided with a locking mechanism constructed in accordance with my invention, 35 said mechanism being shown in its locked position. Fig. 2 is a vertical longitudinal sectional view of a trunk, the locking mechanism being shown in rear elevation and in the position it occupies when the trunk is unlocked. Fig. 3 is a detail in perspective of the escutcheon-plate; Fig. 4, a detail in perspective of the lock-case, the view being taken 40 from the rear. Fig. 5 is a side elevation of the same. Fig. 6 is a front elevation of the lock-case and its contained mechanism, the face-plate being removed to expose the interior and the bolt being shown as shot. Fig. 7 is a view 45 similar to Fig. 6, the bolt being shown as retracted or withdrawn. Fig. 8 is a rear elevation of the lock or face-plate. Fig. 9 is a view 50 similar to Fig. 6, the tumblers being removed.

Fig. 10 is an elevation of the diaphragm or partition-plate. Fig. 11 is a detail in elevation of the key employed. Fig. 10^a shows the tumblers in detail.

55

Like numerals of reference indicate like parts in all the figures of the drawings.

As before indicated, the locking mechanism to be described as of my invention may be usefully employed in various relations, and therefore, although primarily intended for use in connection with trunks and satchels, and illustrated and described herein in connection with a trunk, yet I would have it understood that the application of the invention is by no means 60 limited to the use herein suggested, nor do I consider myself limited to the minor details of construction necessarily employed in this particular application, but contemplate such changes in the details as may be found necessary in different applications of the lock and which will readily suggest themselves to those persons skilled in the art.

In the present instance, 1 designates the body of the trunk, and 2 the usual lid. Secured to the interior of the lid are plates 3, located near the ends, and formed integral with or rigidly secured to said plates are depending keepers 4, the same passing the meeting-line between the lid and trunk-body and therefore extending into the latter. Keepers 5 are secured to the inner surface of the front wall of the trunk-body in line with the keepers 4 and between the same, and loosely supported for reciprocation in the keepers 4 85 are opposite locking-bars 6, the same being designed to be operated in a manner and by mechanism hereinafter described, so as to be shot into the keepers 4 or withdrawn from the same, thus locking the lid or unlocking 90 the same at its opposite ends and obviating the necessity of employing snaps, straps, or other auxiliary fastening means. The front wall of the lid is provided with an internal keeper 7, and below the same the front wall 95 of the trunk-body has formed therein a circular opening in which is located the lock mechanism, which I will now proceed to describe.

Set into the opening formed in the front 100 wall of the trunk is a cylindrical metal bushing 8, the same being formed as a part of an

escutcheon-plate 9, that is applied to the outer surface of the trunk and secured thereto by bolts or screws let into its corners and into the wall of the trunk. At one side the bushing 13 is provided with a keeper or opening 10, and at its opposite side with a slot 11, at one end of which is located a spring-trip 12, that serves as a trip and is normally projected inwardly, but is capable of being compressed 10 within the slot 11. Extending inwardly from the bushing is a stop-lug 13. The bottom of the bushing is provided with a reduced opening 14. A back plate 15 reinforces the escutcheon-plate thus described and has openings 15 corresponding to those in said plate.

16 designates a cylindrical lock-case, the same being of such diameter as to adapt it to fit loosely for rotation within the bushing of the escutcheon. The lock-case comprises 20 a bottom and a surrounding rim, the latter having formed at one side a slot 17, and at the opposite side a bolt-opening 18. Upon its back there is formed a boss 19, from the center of which projects a rectangular gudgeon 20, and from the center of the gudgeon projects a threaded stud 21. The cylindrical portion of the lock-case as well as the cylindrical boss 20 are contained wholly within the bushing of the escutcheon, while the gudgeon 25 and stud project rearwardly beyond the reinforcing-plate 15.

22 designates a hook-shaped rock-arm, the same having a hub 23 at one end that is provided with an angular opening that fits 35 over the gudgeon 20 of the lock-case. Pivoted eccentrically, as at 24, to the hub of the rock-arm 22 are the inner ends of the locking-bars 6. The rock-arm is held in position upon the gudgeon 20 by means of a nut 25, 40 so that by a partial rotation of the lock-case and the rock-arm carried thereby it will be obvious that the locking-bars will be reciprocated accordingly and caused to engage or disengage with the keepers 4 in accordance 45 with the direction of rotation imparted to the lock-case. The partial rotation given the lock-case and the hook-shaped rock-arm in addition to causing a locking engagement at the ends of trunk-lid causes a similar locking 50 and unlocking by throwing the hook-shaped rock-arm into or withdrawing it from engagement with the central keeper 7, as plainly shown in Figs. 1 and 2.

55 Near the center of the bottom of the lock-case there is formed an outstanding stud 26, the same being square in cross-section, and mounted for reciprocation on the stud and in the opening 18 in the rim of the lock-case is a bolt 27. This bolt is provided with a longitudinal slot 28, that loosely fits the stud 26, and interposed between the side of the stud and the forward end of the slot and lying within the same is a coiled expansion-spring 29. The under edge of the bolt is recessed 60 to produce a shoulder 30 near its rear end. The outer face of the bolt is provided at its upper rear corner with an outstanding stud

31 and at its upper front corner with a stud 33 and in line with its slot and in advance thereof with a stud 32.

70 34 designates a diaphragm or partition-plate, and the same is provided with openings 35, that register with similar openings 36, formed in the base of the lock-case for the reception of screws employed for retaining the lock-plate in position. A slot 37, that is formed in the partition-plate, accommodates the stud 31, and below the same an angular opening 38 accommodates the rectangular stud 26. The partition-plate is held 80 in position by means of its recesses 39, which engage with ribs 40, formed on the lock-case. The lower end of the partition-plate is provided with a keyhole-slot 41, and the circular portion of the same is concentrically arranged 85 with reference to the usual key-guiding stud 42, formed on the lock-case.

90 Encircling a stud 43 is a light spring 44, the lower end of which bears against the wall of the lock-case and the upper terminal 95 of which bears against a vertical shoulder 45, with which the outer face of the bolt is provided and which is produced in the bolt by a widening of the same at its forward end.

95 Mounted loosely on the stud 32 is a pair of tumblers 46 and 47, the same having their forward ends perforated to receive the stud 32. The tumbler 46 is provided with a slot 48, the same extending longitudinally, and at its forward end is recessed or offset at its upper side, as at 49, and at its lower side at its rear end recessed or offset, as at 50. The tumbler 47 is likewise provided with a longitudinal slot 51, the rear end of which is recessed or offset at both its upper and lower 105 sides, as indicated at 52.

110 Loosely coiled upon the stud 33 of the bolt is a pair of light springs 53, the upper terminals of which take under the stud 31 and the lower terminals of which bear respectively 115 on the two tumblers 46 and 47. The tumbler 46, which is arranged in rear of the tumbler 47, is provided with a trip-arm 54, which is arranged in line with the slot 17 of the lock-case. When the bolt is retracted, the trip-arm extends through the slot or into the same and into the path of the spring-trip 12; but when the bolt is shot the arm 54 is out of the path of the trip. Through the longitudinal slots 48 and 51 passes the angular stud 26, 120 and the same takes into the various offsets 49, 50, and 52 in accordance with the relative positions assumed by the tumblers and as influenced by the bolt.

125 Arranged to close the front of the lock-case is the lock-plate 55, and the same has formed on its rear side pairs of lugs 56, that engage the ribs 40. As a further means of securing the plate in position screws are passed through holes 57, formed in the lock-plate, and similar holes 35 and 36, formed in the partition-plate and bottom of the lock-case. Near the bottom of the lock-plate is formed the key-hole-opening 58, the same being in line with

the key-guiding stud 42. Diametrically opposite the circular portion of the keyhole 58 is a circular opening 59, formed in the lock-plate.

5 The key 60 (shown in Fig. 11) comprises an offset shank 61, having circular lugs 62 arranged on one face, the distance between the lugs agreeing with the distance between the circular portion of the keyhole 58 and the 10 diametrically opposite opening 59, formed in the lock-plate. At its middle the key may be provided with an angular opening forming a nut-receiving socket 63 for loosening or tightening the nut 25 of the lock mechanism. 15 Beyond the wrench portion 63 of the key there is produced the usual spindle 64, the same being bored to fit and rotate upon the key-guiding stud 42. At one side the spindle is provided with the recessed web 65, the 20 same being formed so that in turning when the bolt is shot, as shown in Fig. 6, it first raises the tumbler 47, the upper offset of whose slot is in engagement with the stud or post 26. The web next comes in contact with the shoulder 30 of the lock-bolt, which may 25 now be withdrawn against the tendency of its springs, inasmuch as the tumbler 47 does not resist such withdrawal by abutting against the stud or post 26.

30 The unlocking, it will be seen, is secured by a movement of the key to the right, and as the bolt and tumblers are carried to the rear the offset 49 of the rear tumbler 46 is spring-pressed into engagement with the stud 26 and retains the bolt in a withdrawn position until the said tumbler 46 is raised against the tension of its spring 53, when it will disengage with the angular stud 26, and the bolt being released will automatically be shot into 35 engagement with the opening 10 in the bushing. Such disengagement of the tumbler 46 is caused by the trip-arm 54 thereof coming in contact with the spring-trip 12 as the lock as a whole is rotated within the bushing by 40 means of a key which is reversed, so that its lugs 62, which constitute a spanner-wrench, engage the circular opening of the keyhole 58 and the diametrically opposite opening 59, formed in the lock-plate.

45 Surrounding the lock thus formed and screwed to the escutcheon is a retaining-ring 66, which overlaps the lock, holding it rotatably within the bushing of the escutcheon, and although this ring may be readily removed yet the nut 25 will serve to retain the lock in position. The ring therefore is more of an ornament and also serves to close the space that occurs between the lock-case and the bushing.

50 In operation, taking the parts in the position they occupy in Fig. 1, the key is first introduced and rotated to the right, operating to withdraw the bolt in the manner heretofore described, after which the key is withdrawn and the lugs 62 introduced into the openings mentioned in the lock-plate, and the key, being employed as a spanner-wrench,

is partially rotated to the left. The lock, operating as an eccentric, will immediately withdraw the locking-bars and hook-shaped locking rock-arm to the positions shown in Fig. 2, thus permitting the trunk to be opened. To lock the trunk, it is simply necessary to close the lid and employ the key as a spanner-wrench, so as to rotate the lock to the right, 75 and the same again acting as an eccentric throws the locking-bars and the hook-shaped locking rock-arm into engagement with their respective keepers. At the same time the trip-arm 54 of the tumbler 46 comes against the spring-trip 12, which causes a lifting of the tumbler from its engagement with the stud 26 and a liberation of the bolt that permits it to be actuated or shot by its springs into the opening 10 of the bushing, with which 80 it at that instant registers. The ends of the slot 17 operate at opposite sides of the stop 13 in the bushing and the latter serves to limit the throw of the lock-case.

85 It will thus be seen that the locking is automatic, while the unlocking is first necessary, after which a bodily movement of the lock-case is required.

90 From the foregoing description, in connection with the accompanying drawings, it will be seen that I have provided a locking mechanism of economic and simple construction and which is adapted for locking a trunk, traveling-satchel, or other device at both the center and ends simultaneously, thus doing 95 away with the necessity of employing trunk-straps, end snaps, or other extraneous fastening devices, and, furthermore, that the parts of this lock do not extend beyond the surface of the trunk and cannot become smashed or 100 damaged, so as to render them inoperative, by 105 careless handling.

110 It is obvious that the lock-case, without internal mechanism and adapted to be operated merely by the spanner-wrench, may be employed in connection with the hook-shaped rock-arm and its keeper at the corners of the trunk, thus serving merely as a corner-catch for same.

Having described my invention, what I 115 claim is—

1. The combination with a trunk or other receiver, the cover of which is provided with opposite end keepers, of a rotary lock mounted on the trunk, means for engaging the bolt of the same with the wall of its support, and locking-bars eccentrically connected in a pivotal manner with the lock and adapted to be thrown into and out of engagement with the said keepers by the rotations of the lock, substantially as specified.

2. The combination with a trunk or other receiver, of a rotary lock, a support for the same with the wall of which the bolt of the lock is adapted to engage, opposite keepers arranged on the lid of the receptacle at the opposite sides of the lock, a keeper above the lock on said lid, a hook-shaped rock-arm carried by the lock and adapted to engage the

- central keeper, and opposite locking-bars eccentrically pivoted to the lock and adapted to be thrown into and out of engagement with the keepers by the movements of the lock, 5 substantially as specified.
3. The combination with a trunk or other receptacle, the lid of which is provided with a keeper, of a support below the lid, a rotatable lock mounted in the support, the bolt 10 of the lock being adapted to engage with said support, and a hook-shaped rock-arm carried by the lock and adapted to be thrown into and out of engagement with the keeper by the movements of the lock, substantially as 15 specified.
4. The combination with a trunk or other receptacle, of a rotary lock, a support for the same with the wall of which the bolt of the lock is adapted to engage, a keeper carried 20 by the lid of the trunk or receptacle, and a locking-bar pivotally connected with the lock and adapted to be thrown into and withdrawn from engagement with the same by the rotations of the lock, substantially as specified.
5. The combination with a trunk or other receptacle having a recess or opening, of an escutcheon-plate secured to the face of the same and provided with a central recess seated 25 in the opening, a rotary lock mounted in the recess of the escutcheon-plate, the bolt of said lock being adapted to engage in the wall of the recess of said plate, keepers carried by the lid of the receptacle, and locking-bars eccentrically pivoted to the lock and adapted to be 30 thrown into engagement with the keepers or be withdrawn therefrom by the movements of the lock, substantially as specified.
6. The combination with a trunk or other receptacle having an opening, a bushing seated 35 in the opening and provided at one side with a hole or keeper and at the opposite side with a trip, of a rotary spring-lock mounted in the bushing and having a bolt-releasing device adapted to be projected in the path of 40 the trip, a keeper carried by the trunk or receptacle lid, and a locking-bar eccentrically pivoted to the lock and adapted to be thrown into and withdrawn from engagement with said keeper by the movements of the lock, 45 substantially as specified.
7. The combination with a trunk or other receptacle having an opening below its lid, of a rotary spring-lock mounted in the opening and provided with a bolt-releasing arm, a 50 tripping device arranged in the path of the releasing-arm whereby the bolt is liberated to engage a recess formed in the wall of the opening, openings formed in the lock-plate and adapted to receive a spanner-wrench, a keeper 55 carried by the lid and a locking-bar eccentrically pivoted to the lock and adapted to be thrown into engagement with the keeper or withdrawn therefrom by the movements of the lock, substantially as specified.
8. The combination with a trunk or other receptacle, the lid of which is provided with 60 keepers, of a lock rotatably mounted in a sup-

port, the bolt of which is adapted to be withdrawn from engagement with the support by means of a key, locking devices for engaging 70 the keepers carried by the lock and operated thereby and means for automatically shooting the bolt of the lock when the lock has been rotated to such a position as to cause the locking devices to engage with the keepers, substantially as specified. 75

9. The combination with a trunk or other receptacle, the lid of which is provided with keepers and the wall of the receptacle portion of which is provided with an opening, of 80 an escutcheon-plate surrounding the opening and provided with a bushing seated in the opening, said bushing having at one side a bolt-hole, at its opposite side a spring-trip and above the same provided with a stop-lug, 85 a cylindrical lock mounted for rotation in the bushing and having a segmental lock for the reception of the stop-lug, said lock having a spring-actuated bolt for engaging the hole in the bushing, and a bolt-liberating arm extending in the path of the trip, and locking devices carried by the lock and adapted to be operated by the movements thereof so as to engage with or be disengaged from the keepers of the lid, substantially as specified. 90

10. The combination with a trunk or other receptacle, the lid of which is provided with keepers and the receptacle portion of which is provided with a bushed opening having at one side a bolt-hole, of a cylindrical lock having a bolt-engaging hole and mounted in the said bushing, said lock being provided at its rear side with a rectangular gudgeon and beyond the same with a threaded stud, opposite locking-bars eccentrically pivoted on the lock 105 and adapted to engage the keepers, a hook-shaped rock-arm having an angular opening carried by the gudgeon and adapted to engage one of the keepers, and a nut arranged on the stud, substantially as specified. 110

11. The combination with a receptacle, of a rotary lock-case supported therein, a slotted bolt arranged in the lock-case and moving over and receiving an angular stud, tumblers pivoted on the stud carried by the bolt and 115 having recesses for receiving the stud upon which the bolt is mounted and adapted to engage therewith when the bolt is either retracted or shot, a key for retracting the bolt and raising the tumbler that holds the same in its shot position, a spring for throwing the bolt and means for raising that tumbler that locks the bolt in its retracted position, such means being so located as to operate only when the case is revolved toward the same, and locking 120 devices for engaging the keepers, said devices being operated by the rotations of the case, substantially as specified. 125

12. The combination with a trunk or other receptacle, the lid of which is provided with 130 keepers and the receptacle portion of which is provided with a cylindrical bush opening having a hole at one side and a trip at the other, of a rotatable lock-case mounted in the

bushing, locking devices operated by the lock-case for engaging with the keepers, a stud projecting from the lock-case, a bolt mounted on the stud and slotted to receive the same and adapted to engage the opening in the bushing, a spring for throwing the bolt, a key-engaging shoulder formed on the lower edge of the bolt, a key-guiding stud below the same, a tumbler pivoted on the bolt and provided 5 at one end with an arm extending into the path of the trip, said tumbler having a longitudinal slot provided at its front end with an offset for engaging the guide-stud of the bolt when the latter is retracted, a second tumbler pivoted on the bolt and having a longitudinal slot provided at its rear end with an offset for engaging said guide-stud, springs 10 for depressing the tumblers, and a lock-plate arranged on the lock-case and having a key-hole-opening registering with the key-guiding stud and diametrically opposite the same provided with a second opening whereby a spanner-wrench may be employed for rotating the lock, substantially as specified.

15 13. The combination with a trunk or other receptacle provided with a bushed opening having a bolt-hole at one side and a trip at the opposite, of a rotatable lock-case seated in the bushing, means for retaining the case in position, locking devices carried by the case and operated by its movements so as to engage or disengage with the keepers, an angular stud, 26, extending from the case, a reciprocating bolt, 27, having a slot, 28, mounted on the stud and provided with the upper end studs, 31 and 33, and the lower stud, 32, and at its lower edge with a shoulder, 30, the diaphragm arranged over the bolt and having the key-hole-opening, 41, and the stud-receiving open-

ings, 35, 37 and 38, the tumblers, 46 and 47, 40 pivoted on the stud, 32, the tumbler 46 having the trip-arm, 54, extending through a slot in the case and into the path of the trip of the bushing when the bolt is retracted, and provided with the longitudinal slot, 48, having 45 the offset, 49, at its front end for engaging the stud, 26, the latter tumbler having the longitudinal slot, 51, having the offset, 47, at its rear end for engaging the stud, 26, the springs, 53, coiled on the stud, 33, and having 50 their terminals interposed between the stud, 31, and the tumblers, 46 and 47, the spring, 44, for throwing the bolt and the lock-plate 55, having the keyhole-opening, 58, and the diametrically opposite opening, 59, substantially as specified. 55

14. The herein-described key, the same consisting of the shank having a web at one end for operating the bolt and at its opposite end provided with a pair of spaced-apart lugs 60 adapted to serve as a spanner-wrench, in combination with a rotatable lock having diametrically opposite openings for receiving the lugs, substantially as specified.

15. The combination with a trunk and lid, 65 of a keeper mounted in the latter, a cylindrical case swiveled in the trunk below the keeper, and adapted to be operated by a wrench, and a hook-shaped rock-arm carried by the case and adapted to be thrown into 70 engagement with the keeper, substantially as specified.

In testimony whereof I affix my signature in presence of two witnesses.

CHARLES E. PARKER.
